UNITED STATES PATENT OFFICE

MARTIN H. BLANCKE, OF MERSEBURG, GERMANY.

SEMI-AUTOMATIC REVOLVING LATHE WITH SEVERAL MANDRELS.

No. 900,007.

Specification of Letters Patent.

Patented Sept. 29, 1908.

Application filed October 29, 1907. Serial No. 399,767.

To all whom it may concern:

Be it known that I, MARTIN H. BLANCKE, a citizen of the German Empire, and resident of Merseburg, Germany, have invented certain new and useful Improvements in Semi-Automatic Revolving Lathes with Several Mandrels, of which the following is a specification.

This invention relates to a semi-automatic revolving lathe in which several mandrels are so arranged that castings up to a certain size of about 700 mm. diameter can be worked on the lathe. The lathe is started by hand while, when the work is finished, the lathe is arrested automatically. The number of mandrels depends on the different working phases an object has to go through, but such objects may, of course, also be worked on a lathe with several mandrels which require fewer working processes. A suitable locking device prevents an arbitrary shifting of the revolving head or the nose of the mandrel. The head is not moved as hitherto by a cam or some similar means, but by a screw spindle, which produces a reliable forced motion.

The drawing shows one embodiment of a semi-automatic revolving lathe, according to the present invention.

Figure 1 is a side view; Fig. 2 is a longitudinal section; Fig. 3 is a top view; Fig. 4 is a cross section on the line A—B, Fig. 2, looking in the direction of the arrow 8; Fig. 5 is a cross section on the line C—D, Fig. 2, looking in the direction of the arrow 9. Fig. 6 shows the tool head in front view and shows the frame of the driving gear of the head in cross section on the line E—F, Fig. 2; and Fig. 7 shows a system of wheels of the revolving head.

Similar numerals refer to similar parts throughout the several views.

The construction of the semi-automatic revolving lathe is as follows: The revolving head, which is provided with six mandrels 10, consists of two journal disks 11 (Fig. 2) which are connected by a bush 12 and are journaled in the part 13 of the frame. The revolving head is turned by means of a screw spindle 14, which is driven by a belt pulley 15. In order to secure the revolving head in its different positions the head is provided with recesses 16 (shown in Fig. 5 in dotted lines), into which enters the bolt 18 in the oscillating lever 17, which bolt can be shifted in the part 13 of the frame. The lever 17,

which is pivoted on the pin 19, also forms the disengaging lever for the coupling sleeve 21, by which the screw spindle 14 is coupled with the driving shaft 20. The lever 17 is held in the position shown in Fig. 5 by a spring 22 and is retained in this position by one arm of a double armed lever 24 pivoted at 23. To the other arm of the lever 24 is attached a weight 25, the arm being supported by a rail 26 having an inclined surface. The rail 26 is secured to the tool head 37 to move therewith. When the tool head reaches a predetermined position, the inclined surface of the rail raises one end of the lever 24 and moves the opposite end of the lever out of engagement with the lever 17. The bolt 18 can then be withdrawn from the recess 16 by means of the handle 56 (see Fig. 5). This causes the lower end of the lever 17 to shift the coupling sleeve 21 to couple the screw-spindle 14 to the shaft 20.

The mandrels 10 are driven by the driving spindle 27 which is provided with two wheels 28 and 29. Each mandrel is provided with two loose rotatable wheels 30 and 31 and a shiftable coupling sleeve 32. Through intermediate wheels 33, the wheels 30 engage the wheel 28 and the wheels 31 engage the wheel 29 directly. In the bush 12 are oscillatingly journaled as many coupling levers 34 as there are mandrels. Each of these coupling levers is under the action of a spring 35 which tends to hold the lever 34 in the position in which it connects the coupling sleeve 32 with the wheel 31. The mandrels therefore all turn to the left. Between position z and position x (Fig. 4) the coupling lever 34 is shifted by the slanting guide 36 (shown in dotted lines in Fig. 3 and also shown in Figs. 1, 2 and 4) in such a manner that the coupling sleeve appertaining to the coupling lever is coupled with the wheel 30, which causes the mandrel to turn to the right. This is necessary in order to provide the work-piece with a thread. The end of the slanting guide 36 is formed by a vertically shiftable sliding piece 38, which is held by a spring in its uppermost position and is drawn downwards by a wedge 40, when the coupling lever is to be released to again couple the mandrel with the wheel 31 to rotate the same to the left, so that the tool can be turned out of the work-piece. This reversing takes place at the commencement of the return movement of the tool head 37. The wedge 40 is mounted on the rail 26 and can be adjusted thereon.

The frame 13, as will be seen from Figs. 1, 3 and 4, is further provided with a guide 41; the object of which is to stop the mandrel in position *y* by bringing the respective coupling lever 34 into the intermediate position, in which the coupling sleeve 32 is out of engagement with both of the wheels 30 and 31. This is necessary for replacing the finished piece by an unwrought one.

10 The head 37 can be shifted in the frame like a sliding carriage. It is moved by means of a screw spindle 42 which is driven by a chain gear 43 through a counter shaft 44, which is driven by the shaft 45. The rail 26 15 is connected with the tool head to move therewith.

On the shaft 45 are journaled several gears for different speeds, which can be coupled alternately with the shaft 45 by means of 20 coupling sleeves 46, 47. The coupling sleeves are moved by levers 48, 49 which are drawn by springs 50 towards one side and are held by detent pins 51 in a certain position. Each 25 detent pin is pressed downwardly by a spring and can be released by means of a lever 52 and raised by a projection 53 or 54 provided on the sliding carriage of the tool head (see 30 Figs. 1 and 6). In a like manner each of the levers 48, 49 can be shifted by a projection 35 58 or 55 provided on the sliding carriage.

Fig. 8 shows the wall 37^a which is also seen to the right of Fig. 6 and is hanging downwards and provided with two slots in which the projections 53, 54, 55 and 58 can be adjusted. The projections 55, 58 are formed by bent pieces of metal or bent screw bolts which can be fixed in the lower slot while the 35 projections 53, 54 are oscillating on bolts which can be fixed in the upper slot and are 40 provided at their upper end with a slanting surface, which passes below the free end of the lever or levers 52. The lower end of each projection 53, 54 rests, on the other hand, against a projection 53^a and 54^a, which can 45 be fixed in the lower slot. Each of the two projections 53, 54 can therefore, when the sliding carriage with the tool moves backwards, move out of the way of the respective 50 switch lever 52, while during the effective movement the projections 53^a, 54 prevent a lateral yielding.

The action of the revolving lathe is as follows: If the mandrel at *y* is provided with the work-piece and the latter has been adjusted, and if the tool head 37 is in its end position, in which the rail 26 has raised the lever 24, the handle 56 is pulled. The bolt 18 is thereby withdrawn from the recess 16 and the screw 14 is coupled with the shaft 20. 55 The revolving head turns until the bolt 18 drops into the next recess 16, whereby the screw 14 is again uncoupled from the shaft 20. If this has been done the lever 48 is moved to the left, in which position it is held 60 by a detent bolt 51, so that the coupling 46

is connected with the driving gear 57, whereby a rapid advance of the tool head is produced. At the moment the tools are to come in contact with the work-pieces, the projection 53 raises the lever 52, so that the bolt 51 again releases the lever 48, and the latter under the action of the spring then connects the coupling 46 with the gear 59. The feed motion proceeds now slowly until the work-piece is finished. At the end of the feed motion, which can be regulated at will, 75 the lever 48 is brought by the projection 55 into the intermediate position and the feed device is thereby disconnected. But at the same time the detent of the lever 49 is released by the projection 54 and this lever is therefore moved to the right by its spring, so that the coupling sleeve 47 comes into contact with the gear 60 and a slow return movement of the tool head takes place. As soon 80 as the tools have left the work-pieces, the lever 49 can be moved to the left by hand, so that the coupling sleeve 47 engages the gear 61 and a rapid return movement of the tool head is effected. In the end position of the 85 tool head, the lever 49 is brought into the intermediate position by the projection 58 and the device for the return movement is disconnected. From the foregoing it will be understood that the coupling lever 34 is shifted by 90 the guide 36 during the first part of the forward movement of the tool head 37. When the revolving head reaches the position in which the coupling lever abuts against the sliding piece 38 the bolt 18 drops into a recess 16 to lock the revolving head against rotation and the coupling lever is held in the shifted position by the sliding piece 38 during the further advancing movement of the tool head, thus causing the mandrel to turn 100 to the right. When the tool head reaches its foremost position the wedge 40 draws the sliding piece 38 downwardly out of engagement with the coupling lever thus permitting the spring 35 to return the coupling lever to 105 its normal position. While the tool head returns the mandrel therefore turns to the left to cause the tool to be turned out of the work-piece. Suitable detents may be provided to cause the levers 48, 49 to remain in 110 the intermediate position. At each movement of the revolving head the work-piece is brought into contact with another tool and, as already mentioned, in the position *x*, Fig. 4, threads can be cut. If it is desired to 115 work with a fore- and after-cutter, a guide similar to the guide 36 may be provided at *z*.

Having thus described my invention, what I claim as new therein and desire to secure by Letters Patent is:—

1. In a semi-automatic revolving lathe, the combination with the frame, the slidably mounted tool head, the revolving head and the spindles rotatably mounted in the revolving head, of a driving shaft common to 120

all of the spindles, a pair of loose gear wheels on each spindle, mounted within the revolving head and having connection with the driving shaft whereby they are rotated in opposite directions by the shaft, a coupling on each spindle for coupling either of said gear wheels to its spindle, a spring normally holding the coupling in a position in which it couples one of the gear wheels to the spindle, a shifting lever for each coupling extending outside of the revolving head, an inclined guide fixed on the frame exterior to the revolving head and adapted to engage said shifting levers to cause the shifting levers to shift the couplings into engagement with the other of said gear wheels, a vertically movable slide normally forming the end of said guide, a spring for holding the slide in its normal position, and a track connected to the tool head to move therewith and adapted to shift said slide out of the path of movement of the shifting levers to permit said first-named spring to return the coupling to its normal position.

2. In a semi-automatic revolving lathe, the combination with the frame, the slidably mounted tool head, the revolving head and the spindles rotatably mounted in the revolving head, of a driving shaft, a driving member for the revolving head, means for coupling the driving member to the driving shaft, a locking device for the revolving head, a connection between said locking device and the coupling means whereby the coupling means is held in its inactive position when the locking device is in its locking position, a lever swingingly mounted in the frame and normally engaging the locking device to hold the locking device in locking position, and a member connected to the tool head to move therewith and adapted to shift said lever to permit release of the locking device.

35 holding the coupling in a position in which it couples one of the gear wheels to the spindle, a shifting lever for each coupling extending outside of the revolving head, an

inclined guide fixed on the frame exterior to the revolving head and adapted to engage 40 said shifting levers to cause the shifting levers to shift the couplings into engagement with the other of said gear wheels, a vertically movable slide normally forming the end of said guide, a spring for holding 45 the slide in its normal position, and a track connected to the tool head to move therewith and adapted to shift said slide out of the path of movement of the shifting levers to permit said first-named spring to return 50 the coupling to its normal position.

3. In a semi-automatic revolving lathe, the combination with the frame, the slidably mounted tool head, the revolving head and the spindles rotatably mounted in the revolving head, of a driving shaft, a driving member for the revolving head, means for coupling the driving member to the driving shaft, a locking device for the revolving head, a connection between said locking device and 55 the coupling means whereby the coupling means is held in its inactive position when the locking device is in its locking position, a lever swingingly mounted in the frame and normally engaging the locking device to 60 hold the locking device in locking position, and a member connected to the tool head to move therewith and adapted to shift said lever to permit release of the locking device.

The foregoing specification signed at 70 Berlin, Germany, this seventeenth day of October, 1907.

MARTIN H. BLANCKE.

In presence of two witnesses—

HENRY HASPER,
WOLDEMAR HAUPT.
